Primary Examiner — Jack Reickel*Assistant Examiner* — Michael A Kervin(74) *Attorney, Agent, or Firm* — Reinhart Boerner Van Deuren P.C.(57) **CLAIM**

I claim the ornamental design for the hardware jig, as shown and described.

DESCRIPTION

FIG. 1 is a top, front perspective view of the hardware jig; FIG. 2 is a bottom, rear perspective view thereof; FIG. 3 is a front view thereof; FIG. 4 is a back view thereof; FIG. 5 is a side view thereof; FIG. 6 is a side view thereof showing the side opposite that shown in FIG. 5; FIG. 7 is a top view thereof; and, FIG. 8 is a bottom view thereof. The broken line showing of a hardware jig is for the purpose of illustrating portions of the article and forms no part of the claimed design.
